M. H. MANSFIELD

Clover Huller.

No. 12,462.

Patented Feb. 27, 1855.

UNITED STATES PATENT OFFICE.

MARTIN H. MANSFIELD, OF ASHLAND, OHIO.

HULLING AND CLEANING CLOVER-SEED.

Specification of Letters Patent No. 12,462, dated February 27, 1855.

To all whom it may concern:

Be it known that I, MARTIN H. MANSFIELD, of Ashland, in the county of Ashland and State of Ohio, have invented a new and useful Improvement in Clover Hulling and Cleaning Machines; and I do hereby declare that the following is a full and exact description thereof, reference being had to the accompanying drawings, 10 making a part of this specification, Figure 1, being a longitudinal vertical section through the center of my improved clover hulling and cleaning machine; Figs. 2 and 3, side elevations of the machine; Fig. 4, 15 a vertical transverse section in the line $x-x$ of Fig. 3, and Fig. 5 a view of a portion of the machine detached.

Similar letters indicate like parts in all the figures.

20 The nature of my invention consists in the employment of a considerably greater length of screen than has heretofore been used in clover hulling and cleaning machines, and in receiving the seeds which fall from said screen upon an endless apron which conveys the seeds to a receptacle k , placed immediately in front of and near to the winnowing fan d .

The clover hulling cylinder a , and concave b , may be constructed in any well-known or usual manner. The seeds and chaff as they are discharged from the said concave, are thrown upon the screen e . The screen e , may be suspended and vibrated in 35 any well known or usual manner. I generally support the end of the screen which is nearest to the hulling concave, upon a crank shaft l , and suspend its opposite end to stirrups. The said crank shaft imparting to the said screen a compound vertical and longitudinal vibratory movement.

Inclined boards s , s , are secured to the sides of the machine, which serve to concentrate the seeds as they fall from the 45 screen e , and conduct them to the endless apron f .

The long screen e , enables the seeds to be thoroughly sifted from the chaff; the said screen is so long, that a blast of great power 50 will not act with sufficient force at the rear end of the machine to carry off any perfect seeds with the dust. Near to the fan the seeds will be blown some distance to the rearward, but not beyond the reach

of the apron f , which will bring them back 55 and discharge them into the trough k . Should any dust fall upon the apron with the seeds, it will be blown off as it approaches the fan, or at the moment that the apron begins to turn upon its moving cylinder g . 60

Thus it will be seen that the combined use of a long screen, with an endless apron under its entire length moving forward toward the winnowing fan, enables a more powerful blast to be used with safety in the cleaning 65 of small seeds; the effect of which arrangement of the said long screen, endless apron, and strong blast, is to perfectly clean the seeds at a single operation, which has never been done by any other machine. 70

A screen i , works in the seed trough k , and conducts the seeds into the bottom of the elevator box n , where they are acted upon and elevated by the elevators upon the band p , which discharges them at the 75 spout g , where a bag may be placed to receive them.

The various parts of the machine are connected to each other as follows—viz: A pulley t , on the shaft of the hulling cylinder a , is banded to the pulley u , on the crank shaft l ; a pulley v , on the said crank shaft, is banded to the pulley i' , on the shaft of the screw i ; a pinion on the shaft of the screw i , works into the cog wheel g' , on the roller g ; and the pulley v , on the shaft of the fan d , is banded to the pulley w , on the shaft of the hulling cylinder. The elevator band p passes around the pulley y , on the outer end of the screw i and receives motion therefrom. 80 85 90

What I claim as my invention and desire to secure by Letters Patent, is—

The arrangement and combined operation of the screen e , the endless conveyor f , 95 and the fan d , in such a manner as to enable a strong blast to be employed without wasting the seeds, substantially as herein set forth.

The above specification of my new and 100 useful improvement in clover seed hulling and cleaning machines signed this 28th day of Decr. 1854.

MARTIN H. MANSFIELD.
